Primary Examiner — Abraham Bahta*(74) Attorney, Agent, or Firm* — Keeley DeAngelo LLP;
W Scott Keeley(57) **CLAIM**

The ornamental design for a dispenser for hand sanitizer, as shown and described.

DESCRIPTION

FIG. 1 is a front-perspective view of a dispenser for hand sanitizer shown worn by a person to show context; FIG. 2 is a front perspective view of the present embodiment;

FIG. 3 is a front perspective view of the present embodiment in an open position;

FIG. 4 is a front view of the present embodiment;

FIG. 5 is a rear view thereof;

FIG. 6 is a right view thereof;

FIG. 7 is a left view thereof;

FIG. 8 is a top view thereof; and,

FIG. 9 is a bottom view thereof.

The broken lines showing portions of the dispenser for hand sanitizer and the environment in FIGS. 1, 2 and 4 are included for the purpose of illustrating and form no part of the claimed design.
